UNITED STATES PATENT OFFICE

128,937

DESIGN FOR A CANISTER OR SIMILAR CONTAINER

Marcelline E. Goubler, Chicago, Ill., assignor to Owens-Illinois Can Company, Wilmington, Del., a corporation of Delaware

Application July 3, 1941, Serial No. 101,892

Term of patent 7 years

To all whom it may concern:

Be it known that I, Marcelline E. Goubler, a citizen of the United States, residing at Chicago, in the county of Cook and State of Illinois, have invented a new, original, and ornamental Design for a Canister or Similar Container, of which the following is a specification, reference being had to the accompanying drawing, forming a part thereof,

In the drawing the figure is a perspective view of a canister or similar container showing my new design. The opposite side of the canister has substantially the same appearance as the side shown.

I claim:

The ornamental design for a canister or similar container, substantially as shown and described.

MARCELLINE E. GOUBLER.
